United States Patent Office

Des. 193,321
Patented July 31, 1962

193,321

VIBRATING LOUNGE

Richard Thomas, 14 9th Place, Long Beach, Calif.

Filed June 27, 1961, Ser. No. 65,737

Term of patent 3½ years

(Cl. D83—1)

FIG. 1.

FIG. 2.

FIG. 3.

FIG. 4.

FIG. 1 is a front elevational view of a vibrating lounge, showing my new design;

FIG. 2 is a top plan view thereof;

FIG. 3 is a rear elevational view thereof; and

FIG. 4 is a left side elevational view of FIG. 1.

The side not shown is substantially like that shown in FIG. 4.

I claim:

The ornamental design for a vibrating lounge, as shown and described.
